TOILET SEAT

Irene C. McQuaid, New York, N. Y.

Application April 5, 1940, Serial No. 327,942

7 Claims. (CL 4—239)

This invention relates to a toilet seat, and more particularly to a sanitary toilet seat cover adapted to support infants on the usual toilet.

An object of this invention is to provide an improved sanitary easily transported toilet seat cover for infants.

Another object of this invention is to provide an easily attached and washable toilet seat.

Still another object of this invention is to form a toilet seat cover for infants which provides adequate support for the child.

A further object of this invention is to provide a toilet seat adapted for use with toilets of various constructions.

A more specific object of this invention is to provide a sanitary toilet seat cover for infants which is suspended between the front of the toilet seat and the top of the toilet seat lid.

Further objects and advantages of this invention will be apparent from consideration of the specification as illustrated by the accompanying drawing of possible embodiments of the invention, in which drawing:

Fig. 1 is a perspective view of a toilet seat formed in accordance with the present invention, as applied to a toilet of ordinary construction;

Fig. 2 is a side view, partially in cross-section, of the toilet and toilet seat shown in Fig. 1;

Fig. 3 is a bottom view of the toilet seat removed from the toilet;

Fig. 4 shows a modified form of toilet seat as applied to a toilet of another construction; and

Fig. 5 illustrates a supplementary seat member which may be attached to the toilet seat of the present invention.

The invention as portrayed in the drawing, and particularly Figs. 1, 2 and 3 thereof, consists of a cover 10, preferably made of some strong and washable material having pockets 12 and 14 formed at opposite ends and an opening 16 adapted to support an infant over the usual bowl. The seat is attached to the toilet proper by slipping the front pocket 12 over the forward edge A of the toilet seat and slipping the rear pocket 14 over the top of the toilet seat lid B. This is preferably done while the lid is in a more or less lowered position, and the lid is then raised while the straps 18 and 20 connecting the front and rear pockets 12 and 14 on the underside of the seat are slipped beneath and along the edge of the toilet seat A, so that the two pockets will be firmly held on their respective enclosures and prevent the seat from slipping off. A strap loop 24 is attached to the outer edges of the pocket 14 and is adapted to slip over a sta-

tionary part of the toilet, such as the valve body C. The seat 10 will then assume a position somewhat as shown in Fig. 2, the seat proper being, as shown in full lines, suspended like a hammock between the top of the toilet seat lid B and the front edge of the toilet seat A. The seat lid B will be seen to assume a substantially vertical or slightly forwardly inclined position. When the infant is seated upon the supplementary seat the latter is drawn to about the position shown in dotted lines where a portion thereof forms a back rest for the infant. Straps 26 and 28 may be provided for attachment about the body of the infant to aid in its support.

15 In case the seat is to be used with the type of toilet having a water tank, the construction illustrated in Fig. 4 may be used. This is identical in all respects with the seat described above in Figs. 1, 2 and 3, except that instead of providing the loop strap 24, in this case I provide a strap 30 attached at one end to the lower edge of the pocket 14, and at its other end to a suitable hook member 32 which may be attached to the front edge of the water tank D. The attachment of the strap 30 to the lower edge of the pocket 14 permits the seat lid to come forward, similarly as shown in Fig. 2 so that the supplemental seat 10 will provide a hammock like suspended support for the infant.

20 30 In connection with the form of invention illustrated in Fig. 4, it is to be understood that the seat illustrated in Figs. 1, 2 and 3 may be also provided with the strap and hook shown in Fig. 4 in addition to the loop 24. If this is done, a single seat may be used with both types of toilet.

35 40 In order to increase the usefulness of my improved cover and adapt it for use with infants of various ages, this cover may be provided with suitable spaced openings such as button holes 34 by means of which a supplementary seating member 36 may be attached by means of buttons 38 on its underside. The seating member 36 is provided with an opening 40 smaller than the opening 16 provided on the original seat 10, so that the seat may be used for infants smaller than could be placed on the original cover.

45 50 It is proposed that the seat of the present invention be formed of some suitable soft material which can be easily transported and quickly laundered. For example, it may be formed with an upper surface of flannel mounted on a base of stronger material. It is to be pointed out, however, that I do not intend to limit myself to any particular material, except that it must be such that it will be strong enough to hold the infant

suspended between the top of the toilet seat lid and the front of the toilet seat. Additionally, it is contemplated that various changes in structure may be made as will be apparent to those skilled in this art. The various straps may be attached to the material in any suitable manner, while the seat opening 16 may be formed and bound in any desirable way. While I have indicated the use of buttons for attaching the supplementary seat to the main seat, other suitable means within the purview of those skilled in this art may be used.

Accordingly, it will be seen that I have provided a construction which satisfies the objects enumerated above, and while I have shown the invention in certain physical embodiments, it is to be understood that modifications in the structure shown may be made by those skilled in this art without departing from my invention as expressed in the following claims.

I claim:

1. A sanitary toilet seat attachment, particularly for infants, comprising a sheet of soft material having an opening therein substantially smaller than the toilet seat opening and formed with pockets on its underside at either end, one pocket being adapted to fit over the forward end of the toilet seat and the other over the top of the toilet seat lid whereby the central portion of the attachment is suspended between said pocketed ends.

2. The combination according to claim 1, in combination with straps on the underside of said attachment, extending from each side of the front pocket to the middle of the lower edge of the

back pocket, adapted to pass beneath and along the outer edges of the toilet seat for preventing the pockets from slipping off the seat front or the lid.

3. The combination according to claim 1, in combination with means attached to the rear portion of said attachment for connection with a stationary part of the toilet to limit forward motion of the seat lid.

4. The combination according to claim 1, in combination with an adjustable strap attached to the rear portion of the attachment and adapted to restrain movement of the person supported thereon.

5. The combination according to claim 1, in which said attachment is provided with a plurality of button holes spaced from and about its opening, in combination with a supplementary cover having a smaller opening and provided with a plurality of buttons on its underside spaced from and about said smaller opening and positioned for engagement with said button holes.

6. The combination according to claim 1, in combination with strap means in the form of a loop attached to the rear portion of said attachment and adapted to pass over and engage a stationary portion of the toilet to limit the forward motion of the seat lid.

7. The combination according to claim 1, in combination with a strap at one end to the rear portion of said attachment, and on its other end provided with a hook adapted to engage the edge of the toilet tank to limit the forward motion of the seat lid.

IRENE C. McQUAID.
